FREQUENCY DETECTOR AND CONTROL
VOLTAGE SUPPLYLloyd M. Hershey, Great Neck, N. Y., assignor to
Hazeltine Corporation, a corporation of Delaware

Application November 13, 1940, Serial No. 365,442

11 Claims. (Cl. 250—20)

The present invention relates to an improved carrier-signal frequency detector and control-voltage supply system and, particularly, to such a system for detecting a frequency-modulated carrier signal and simultaneously deriving from the carrier signal a control voltage which is particularly suited for use as an automatic amplification control bias, tuning indicator control bias, or the like.

It is frequently desirable, from the standpoint of simplicity and economy, to provide a frequency-modulated carrier-signal receiver which does not require an amplitude-limiting system, the function of which is to remove undesirable amplitude modulation from a received carrier signal. The amplitude-limiting system of such a receiver has heretofore frequently been used additionally to supply an automatic amplification control bias by which the signal input to the detector of the receiver is maintained within a relatively narrow range for a wide range of received signal intensities. In the event that the limiting system is omitted from the receiver, it becomes necessary to find another source of automatic amplification control bias. The conventional frequency detector included in such a receiver comprises means for developing a unidirectional voltage across each of two load impedances, one of which voltages is of proper polarity to provide an automatic amplification control bias. However, this voltage is unsatisfactory for automatic amplification control purposes since the magnitude of the bias varies continuously with the mean frequency of the carrier signal over the frequency-response range of the detector, the voltage having minimum and maximum amplitudes at opposite ends of the frequency-response range. Thus, when this voltage is used to control the amplification of the receiver, the amplification varies considerably with detuning and the maximum audible output is obtained when the receiver is badly detuned from the desired carrier signal.

An automatic amplification control bias has been obtained in accordance with one prior art arrangement by designing the primary circuit of the detector frequency-responsive network with a relatively high impedance. A rectifier device and load impedance are coupled across this circuit to derive across the load impedance by rectification of the carrier signal an automatic amplification control bias. This arrangement has the serious disadvantage that the high-impedance primary circuit renders it difficult to obtain a linear output characteristic for the frequency

detector and there is, consequently, material distortion of the modulation components of the carrier signal.

It is frequently convenient to use the automatic amplification control bias also to control a tuning indicator device preferably provided in the carrier-signal receiver as an aid in tuning the receiver exactly to a desired carrier signal. Consequently, it is desirable that this bias be obtained from the output of the detector frequency-responsive network in order that the receiver shall be so tuned that the carrier signal applied to the detector has a mean frequency corresponding to the mid-frequency of the frequency-response range of the detector. Furthermore, from the standpoint of accurate tuning indications, it is desirable that the control bias have an amplitude characteristic with a change of slope at the mid-frequency of the detector response range. While a control bias derived in accordance with the aforementioned prior art arrangement, comprising a high-impedance primary circuit having a rectifier device and load impedance coupled thereto, may have this type of amplitude characteristic, the control bias is not normally satisfactory for tuning indication purposes since the change of slope of the characteristic does not necessarily occur exactly at the mid-frequency of the detector response range and, in fact, does not ordinarily occur at the mid-frequency if the detector is designed for a carefully balanced output. Such control bias is also unsatisfactory from the standpoint that it is not derived from the output of the detector frequency-responsive network.

It is an object of the present invention, therefore, to provide a new and improved combined carrier-signal frequency detector and control-voltage supply which avoids one or more of the disadvantages and limitations of the prior art devices.

It is a further object of the invention to provide a carrier-signal frequency detector and control-voltage supply wherein the detector frequency-responsive network has a low-impedance primary circuit to ensure linearity of the output characteristic of the frequency detector and wherein there is developed from the output circuit of the network a unidirectional control voltage having a characteristic suitable for use either as an automatic amplification control bias or as a control bias for a tuning indicator device, or for both.

It is a further object of the invention to provide a control-voltage supply for developing by

rectification of a received carrier signal two unidirectional control voltages having over a predetermined range of frequency deviation of the carrier signal similar amplitude characteristics but opposite polarities.

It is an additional object of the invention to provide a control-voltage supply for deriving by rectification of a frequency-modulated carrier signal a control voltage having an amplitude characteristic with an abrupt change of slope at the exact mid-frequency of the detector frequency-response range, whereby the derived voltage is especially suitable as a tuning indicator device control voltage.

In accordance with a preferred form of the invention, a combined carrier-signal frequency detector and control-voltage supply comprises a frequency-selective network including two sections having predetermined frequency-response characteristics of the same type but sloping in opposite senses with frequency over a predetermined range of frequency deviation of a carrier signal applied thereto. The system includes a modulation-signal detector including a pair of rectifier devices individually coupled to the network sections, each of the devices having an individual load impedance across which there is developed by rectification of the carrier signal a unidirectional modulation voltage. There is also provided a control-voltage supply circuit including an additional rectifier device and a load impedance coupled to one of the network sections to derive by rectification of the carrier signal a unidirectional voltage, and an output circuit for cumulatively combining the last-named derived voltage and a unidirectional voltage derived from the other of the network sections to provide a unidirectional control voltage.

In accordance with a particular form of the invention, a carrier-signal control-voltage supply comprises a frequency-selective network including two sections having predetermined frequency-responsive characteristics of the same type but sloping in opposite senses with frequency over a predetermined range of frequency deviation of a carrier signal applied thereto. There is included a pair of rectifier devices individually coupled to the sections and means including a load impedance common to the rectifier devices for developing across the impedance by rectification of the applied carrier signal a unidirectional control voltage having an amplitude minimum at the mid-frequency and amplitude maxima near the end frequency of the aforesaid range of frequency deviations.

For a better understanding of the present invention, together with other and further objects thereof, reference is had to the following description taken in connection with the accompanying drawing, and its scope will be pointed out in the appended claims.

Referring now to the drawing, Fig. 1 is a circuit diagram, partly schematic, of a complete frequency-modulated carrier-signal receiver of the superheterodyne type embodying the invention; Fig. 2 is a graph comprising curves representing the output of the frequency-responsive network of the frequency detector and the output of the control-voltage supply of the Fig. 1 arrangement; Figs. 3 and 5 are circuit diagrams of modified forms of the invention; and Fig. 4 is a graph comprising curves showing voltage relations at certain points in the arrangement of Fig. 3.

Referring now more particularly to Fig. 1, 75

there is represented schematically a complete frequency-modulated carrier-signal receiver of a conventional design embodying the present invention in a preferred form. In general, the receiver includes a radio-frequency amplifier 10 having its input circuit connected to an antenna system 11, 12, and having its output circuit connected to an oscillator-modulator 13. Connected in cascade with the oscillator-modulator 13, in the order named, are an intermediate-frequency amplifier 14 of one or more stages, a combined carrier-signal frequency detector and control-voltage supply 15, more fully described hereinafter, an audio-frequency amplifier 16 of one or more stages, and a sound reproducer 17. An automatic amplification control or A. V. C. circuit is connected between the output of the control-voltage supply of unit 15 and the input circuits of one or more of the tubes of the radio-frequency amplifier 10, the oscillator-modulator 13, and the intermediate-frequency amplifier 14, in conventional manner.

It will be understood that the various units just described may, with the exception of the carrier-signal frequency detector and control-voltage supply 15, be of conventional construction and operation, the details of which are well known in the art, rendering detailed description thereof unnecessary. Considering briefly the operation of the receiver as a whole, and neglecting for the moment the operation of the frequency detector and control-voltage supply 15 presently to be described, a desired frequency-modulated carrier signal is selected and amplified by the radio-frequency amplifier 10, converted to a frequency-modulated intermediate-frequency carrier signal in the oscillator-modulator 13, amplified in the intermediate-frequency amplifier 14, and detected by the frequency detector of unit 15, thereby to derive the audio-frequency modulation components. The audio-frequency components are, in turn, amplified in the audio-frequency amplifier 16 and are reproduced by the sound reproducer 17 in a conventional manner. A control voltage derived by the control-voltage supply of unit 15 is used as an automatic amplification control of A. V. C. bias and is effective to control the amplification of one or more of the units 10, 13, and 14 to maintain the signal input to the detector of unit 15 within a relatively narrow range for a wide range of received signal intensities.

Referring now more particularly to the portion of the system embodying the present invention, 55 there is coupled to the intermediate-frequency amplifier 14 a frequency-responsive network 18 including two sections 19, 20. The network 18 includes a primary circuit of relatively low impedance comprising windings 21 and 22 coupled respectively to the network sections 19 and 20. The network sections 19 and 20 are individually tuned on opposite sides of the mid-frequency and near the end frequencies of the normal range of frequency deviation of the carrier signal to be translated. There is provided a modulation-signal detector 24 including a pair of rectifier devices 25, 26 respectively coupled to the network sections 19, 20. The rectifier devices 25, 26 have individual load impedances 27, 28, respectively, serially-connected therewith. A control-voltage supply circuit 29 includes an additional rectifier device 30 and a load impedance comprising a load resistor 31 connected in shunt thereto, the device 30 being coupled through a condenser 32 to the network section 19. The load impedances

27, 28 and the load resistor 31 have a common terminal. Unidirectional modulation voltages are developed across the load impedances 27, 28 by rectification of the carrier signal and are combined with opposing polarities and applied to the input circuit of the audio-frequency amplifier 16. An output circuit comprising a filter including a series resistor 33 and shunt condenser 34 cumulatively combines unidirectional voltages derived across the load impedances 28 and 31 to provide a unidirectional control voltage and applies this voltage as an automatic amplification control bias through a conductor designated as A. V. C. to the input circuits of one or more of the tubes of units 10, 13, and 14.

In considering the operation of the circuit just described, and referring to Fig. 2, the frequency-response characteristics of the network sections 19 and 20 are shown by curves *a* and *b*, respectively, and it will be seen that the frequency-response characteristics of the network sections are of the same type and symmetrically disposed relative to the mid-frequency f_0 of the network 18 but slope in opposite senses with frequency over a predetermined range f_1, f_1 of frequency deviation of a frequency-modulated carrier signal applied from amplifier 14 to the network 18. The frequency detector 24 rectifies the carrier signal to derive across the load impedances 27, 28 the modulation components thereof. These modulation components are applied to the audio-frequency amplifier 16 for amplification and eventual reproduction by the sound reproducer 17.

The carrier signal developed across the network section 19 also is rectified by the rectifier device 30 to derive across load impedance 31 a unidirectional voltage which is cumulatively combined by the A. V. C. circuit with that derived across load impedance 28 to derive a negative unidirectional control voltage having an amplitude characteristic represented by curve *c* of Fig. 2. It will be seen that the amplitude of this voltage is substantially constant over the frequency range f_1, f_1 , which is greater than the normal range of frequency deviation of the carrier signal, as is desirable for automatic amplification control purposes.

Fig. 3 is a circuit diagram of a modified form of the invention essentially similar to the arrangement of Fig. 1, similar circuit elements being designated by similar reference characters, except that the control-voltage supply system 29 includes an additional rectifier device 35 coupled through a condenser 36 to the network section 20 of the frequency-responsive network 18 and includes an additional load impedance 38 common to the two rectifier devices 30, 35. As thus arranged, the rectifier devices 30, 35 are individually coupled through the common series load impedance 38 to the network sections 19, 20. Means is provided for connecting the series-related load impedances 31 and 38 in shunt to the rectifier devices 30 and 35 comprising a center-tapped resistor 37 connected between corresponding elements of the latter rectifier devices. A second output circuit comprising a filter including a series resistor 39 and a shunt condenser 40 applies the unidirectional potential derived across the load impedance 38 to a tuning indicator device 48.

The operation of this modified form of the invention is essentially similar to that of the Fig. 1 arrangement. As in Fig. 1, the modulation components of the carrier signal are derived across

the load impedances 27, 28. The carrier signal is rectified by rectifier devices 30, 35 to derive across load impedance 31 a negative unidirectional control voltage and across load impedance 38 a positive unidirectional control voltage. The curves of Fig. 4 represent the magnitudes of these unidirectional voltages with variations of frequency of the intermediate-frequency carrier signal. It will be evident that each of these unidirectional control voltages has an amplitude minimum at the mid-frequency f_0 and amplitude maxima near the end frequencies f_1, f_1 of the range of frequency deviation of the applied carrier signal. Curve *e* shows the magnitude of the voltage derived across the load impedance 31 and curve *d* that derived across load impedance 38. The former unidirectional voltage is suitable for use as an automatic amplification control bias while the latter voltage may be used, for example, as a control bias for the tuning indicator device 48, the change of slope of its characteristic at the mid-range frequency f_0 furnishing an accurate indication when the receiver is accurately tuned to a desired carrier signal. The broken-line curves *a*₁ and *b*₁ extended into individual portions of curve *d* correspond to the curves *a* and *b* of Fig. 2 and represent, as before, the individual frequency-response characteristics of the network portions 19 and 20. It will thus be evident that the amplitude characteristic of the unidirectional voltages developed across the load impedances 31 and 38 correspond to portions of each of curves *a*₁ and *b*₁. This is due to the arrangement of the load impedances 31 and 38 in common to the rectifier devices 30 and 35. As thus arranged, the voltage derived across one or both of the load impedances by that one of the rectifier devices to which the larger amplitude values of carrier signal is applied, when the mean frequency of the carrier signal departs from the frequency f_0 , is sufficiently large to reduce the operativeness of the other rectifier device or, should the mean frequency of the carrier signal depart sufficiently far from the frequency f_0 , even to render the other rectifier device inoperative.

If the impedance of the load impedance 38 is reduced to zero, a unidirectional voltage having the amplitude characteristic represented by curve *e* of Fig. 4 is still derived across the load impedance 31. On the other hand, if the load impedance 31 has a zero value of impedance, a positive unidirectional voltage having an amplitude characteristic represented by curve *d* of Fig. 4 is developed across the load impedance 38. Obviously, by adjusting the values of the load impedances 31 and 38 any desired intermediate magnitudes of control voltages may be procured. Thus, the arrangement of Fig. 3 is capable of deriving two unidirectional voltages of opposite polarities, the magnitude of one or both of the unidirectional voltages being controllable.

Fig. 5 is a circuit diagram representing an additional modified form of the invention which is essentially similar to the arrangement of Fig. 1, similar circuit elements being designated by similar reference characters, except that an additional rectifier device 41 is individually coupled through a condenser 42 to the network section 20. The rectifier device 41 has a load impedance 43 across which there is developed a unidirectional voltage by rectification of a carrier signal applied to network 18. In this modification, the coupling of the rectifier device 30 to the network section 19 is completed through the condenser 32.

and a condenser 44. There is included means for so connecting the load impedances 31 and 43 in the output circuit comprising elements 33 and 34 that the voltages derived across those load impedances are cumulatively combined to provide a unidirectional control voltage. This means comprises an isolating impedance 45 interposed between rectifier devices 30 and 41 to isolate the individual circuits of the rectifier devices for carrier signals while permitting the unidirectional voltages derived across the load resistors 31 and 43 to be cumulatively combined in an output circuit comprising a filter network including the series resistor 33 and the shunt condenser 34.

The operation of this modified form of the invention is essentially similar to that of the Fig. 1 arrangement and will not be repeated, the unidirectional control voltages derived across the load impedances 31, 43 and applied to the output-circuit filter network 33, 34 having the amplitude characteristic represented by curve c of Fig. 2.

From the above description of the invention, it will be evident that the impedances 27, 28 and 31 of Fig. 1, the impedances 27, 28, 31 and 38 of Fig. 3, and the impedances 27, 28, 31 and 43 of Fig. 5 in each instance comprise an impedance network including a plurality of impedance branches. The several rectifier devices of each figure comprise a plurality of rectifier devices for individually coupling these impedance branches to determined ones of the network sections 19, 20 of the frequency-selective network 18. A first output circuit is coupled to the impedance branches 27, 28 to derive a modulation voltage the magnitude and polarity of which vary with the frequency of the carrier signal applied to unit 15 in opposite senses from the mid-frequency f_0 of the range of frequency deviation of the applied carrier signal. A second output circuit, comprising in Figs. 1, 2 and 3 the elements 33, 34 and additionally in Fig. 2 the alternative or additional output circuit elements 39, 40, is coupled to the impedance branches of the impedance network to derive a unidirectional control voltage having an amplitude minimum at the mid-frequency f_0 and amplitude maxima near the limiting frequencies f_1, f_2 of the range of carrier-signal frequency deviation.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A combined carrier-signal frequency detector and control-voltage supply comprising, a frequency-selective network including two sections having predetermined frequency-response characteristics of the same type but sloping in opposite senses with frequency over a predetermined range of frequency deviation of a carrier signal applied thereto, a modulation-signal detector including a pair of rectifier devices individually coupled to said sections, each of said devices having an individual load impedance across which there is developed by rectification of said carrier signal a unidirectional modulation voltage, and a control-voltage supply circuit including an additional rectifier device and a load impedance coupled to one of said sections to derive by rectification of said carrier signal a unidirectional voltage, and an output circuit for cumulatively combining said last-named derived voltage and a unidirectional voltage derived from the other of said sections to provide a unidirectional control voltage.
2. A combined carrier-signal frequency detector and control-voltage supply comprising, a frequency-selective network including two sections having predetermined frequency-response characteristics of the same type but sloping in opposite senses with frequency over a predetermined range of frequency deviation of a carrier signal applied thereto, a modulation-signal detector including a pair of rectifier devices individually coupled to said sections, each of said devices having a serially-connected individual load impedance across which there is developed by rectification of said carrier signal a unidirectional modulation voltage, and a control-voltage supply circuit including an additional rectifier device and a load impedance connected in shunt thereto coupled to one of said network sections to derive by rectification of said carrier signal a unidirectional voltage, and an output circuit for cumulatively combining said last-named derived voltage and a unidirectional voltage derived from the other of said sections to provide a unidirectional control voltage.
3. A combined carrier-signal frequency detector and control-voltage supply comprising, a frequency-selective network including two sections having predetermined frequency-response characteristics of the same type but sloping in opposite senses with frequency over a predetermined range of frequency deviation of a carrier signal applied thereto, a modulation-signal detector including a pair of rectifier devices individually coupled to said sections, each of said devices having an individual load impedance across which there is developed by rectification of said carrier signal a unidirectional modulation voltage, and a control-voltage supply circuit including an additional rectifier device and shunt-connected load resistor coupled to one of said sections to derive by rectification of said carrier signal a unidirectional voltage, and an output circuit for cumulatively combining the voltages derived across one of said impedances and said resistor to provide a unidirectional control voltage.
4. A combined carrier-signal frequency detector and control-voltage supply comprising, a frequency-selective network including two sections having predetermined frequency-response characteristics of the same type but sloping in opposite senses with frequency over a predetermined range of frequency deviation of a carrier signal applied thereto, a modulation-signal detector including a pair of rectifier devices individually coupled to said sections, each of said devices having an individual load impedance across which there is developed by rectification of said carrier signal a unidirectional modulation voltage, and a control-voltage supply circuit including an additional rectifier device and shunt-connected load resistor coupled to one of said sections to derive by rectification of said carrier signal a unidirectional voltage, said load impedances and said load resistor all having a common terminal, and an output circuit for cumulatively combining the voltages derived across one of said impedances and said resistor to provide a unidirectional control voltage.
5. A combined carrier-signal frequency detector and control-voltage supply comprising, a

frequency-selective network including two sections having predetermined frequency-response characteristics of the same type but sloping in opposite senses with frequency over a predetermined range of frequency deviation of a carrier signal applied thereto, a modulation-signal detector including a pair of rectifier devices individually coupled to said sections, each of said devices having an individual load impedance across which there is developed by rectification of said carrier signal a unidirectional modulation voltage, and a control-voltage supply circuit including an additional pair of rectifier devices individually coupled to said network sections, each of said last-named devices having an individual load impedance across which there is derived by rectification of said carrier signal a unidirectional voltage, an output circuit, and means for so connecting said last-named load impedances in said output circuit that said last-named derived voltages are cumulatively combined to provide a unidirectional control voltage.

6. A combined carrier-signal frequency detector and control-voltage supply comprising, a frequency-selective network including two sections having predetermined frequency-response characteristics of the same type but sloping in opposite senses with frequency over a predetermined range of frequency deviation of a carrier signal applied thereto, a modulation-signal detector including a pair of rectifier devices individually coupled to said sections, each of said devices having an individual load impedance across which there is developed by rectification of said carrier signal a unidirectional modulation voltage, and a control-voltage supply circuit including an additional pair of rectifier devices individually coupled to said network sections, each of said last-named devices having an individual load impedance across which there is derived by rectification of said carrier signal a unidirectional voltage, an output circuit, and an isolating impedance interposed between said last-named devices for so connecting said last-named load impedances in said output circuit that said last-named derived voltages are cumulatively combined to provide a unidirectional control voltage.

7. A carrier-signal control-voltage supply comprising, a frequency-selective network including two sections having predetermined frequency-response characteristics of the same type but sloping in opposite senses with frequency over a predetermined range of frequency deviation of a carrier signal applied thereto, a pair of rectifier devices individually coupled to said sections, and means including a load impedance common to said rectifier devices for developing across said impedance by rectification of said applied carrier signal a unidirectional control voltage having an amplitude minimum at the mid-frequency and amplitude maxima near the end frequencies of said range of frequency deviation.

8. A carrier-signal control-voltage supply comprising, a frequency-selective network including two sections having predetermined frequency-response characteristics of the same type but sloping in opposite senses with frequency over

a predetermined range of frequency deviation of a carrier signal applied thereto, and a pair of rectifier devices individually coupled through a common load impedance to said sections to derive across said load impedance by rectification of said carrier signal a unidirectional control voltage having an amplitude minimum at the mid-frequency and amplitude maxima near the end frequencies of said range of frequency deviation.

9. A carrier-signal control-voltage supply comprising, a frequency-selective network including two sections having predetermined frequency-response characteristics of the same type but sloping in opposite senses with frequency over a predetermined range of frequency deviation of a carrier signal applied thereto, a pair of rectifier devices individually coupled to said sections, and a load impedance common to said rectifier devices and connected in shunt thereto to derive by rectification of said carrier signal a unidirectional control voltage having an amplitude minimum at the mid-frequency and amplitude maxima near the end frequencies of said range of frequency deviation.

10. A carrier-signal control-voltage supply comprising, a frequency-selective network including two sections having predetermined frequency-response characteristics of the same type but sloping in opposite senses with frequency over a predetermined range of frequency deviation of a carrier signal applied thereto, a pair of rectifier devices individually coupled to said sections, a load impedance common to said devices and connected in shunt thereto for deriving by rectification of said carrier signal a first control voltage, and a load impedance common to said devices and connected serially therewith for deriving by rectification of said carrier signal a second control voltage having polarity opposite to that of said first control voltage.

11. A combined carrier-signal frequency detector and control-voltage supply comprising, a frequency-selective network including two sections having predetermined frequency-response characteristics of the same type but sloping in opposite senses with frequency over a predetermined range of frequency deviation of a carrier signal applied thereto, an impedance network including a plurality of impedance branches, a plurality of rectifier devices for individually coupling said branches to predetermined ones of said network sections to develop unidirectional voltages across said branches by rectification of said carrier signal, a first output circuit coupled to said impedance branches to derive a modulation voltage the magnitude and polarity of which vary with the frequency of said carrier signal in opposite senses from the mid-frequency of said range of frequency deviation, and a second output circuit coupled to said impedance branches to derive a unidirectional control voltage having an amplitude minimum at the mid-frequency and amplitude maxima near the limiting frequencies of said range of frequency deviation.

LLOYD M. HERSHY.
